(57) **CLAIM**

The ornamental design for a decorated eyewear design, substantially as shown and described.

DESCRIPTION

FIG. 1 is a front orthogonal view of a decorated eyewear in accordance with my design.

FIG. 2 is a top perspective view thereof; and,

FIG. 3 is a front perspective view thereof.

The broken lines are for illustrative purposes only and form no part of the claimed design. The left and right sides of the invention are mirror images of each other.

1 Claim, 3 Drawing Sheets

FIG. I

FIG. 2

FIG. 3
